United States Patent Office

Des. 208,116
Patented July 18, 1967

208,116

JAR OR THE LIKE

Walter Joseph Landor, San Francisco, Calif., assignor to Hills Bros. Coffee, Inc., San Francisco, Calif.

Filed Mar. 7, 1966, Ser. No. 1,335

Term of patent 14 years

(Cl. D58—25)

FIG_1

FIG_4

FIG. 1 is a front elevational view of a jar or the like embodying my new design, the rear being substantially the same in appearance;

FIG. 2 is a side elevational view; the opposite side being substantially the same in appearance;

FIG. 3 is a bottom plan view; and

FIG. 4 is a top plan view thereof.

I claim:

The ornamental design for a jar or the like, as shown and described.
